PUMPROOF SWITCH CONTROL SYSTEM

Alexander C. Boisseau, Lansdowne, Pa., assignor
to General Electric Company, a corporation of
New York

Application February 13, 1942, Serial No. 430,773

8 Claims. (Cl. 175—294)

My invention relates to an electric control system for controlling a single predetermined operation such as a circuit-interrupter closing operation so as not only to insure completion thereof but also to prevent recurrent operations when only a single control operation has been initiated by the operator. More particularly, my invention is in the nature of an improvement on the invention disclosed and claimed in copending application, Serial No. 410,980, filed jointly for Benjamin S. Beall and me, and assigned to the same assignee as the present application.

It is a common expedient in control systems for circuit interrupters to initiate the closing operation by closing a manual switch of some sort. Generally, the closing of this switch initiates the operation of suitable motive means for moving the circuit interrupter to the closed position. If this switch remains in the closed position after the closing operation has been completed and the circuit interrupter immediately opens due to an abnormal condition on the power circuit which it controls, obviously, the closing circuit of the circuit interrupter is again completed as soon as it reaches its open position and the closing operation is repeated. Under these conditions, a circuit interrupter continues to open and close rapidly while the abnormal condition persists and the manual switch remains in its circuit-closing position. This so-called "pumping action" if allowed to continue may result in serious damage to the associated apparatus.

Many antipumping arrangements have been proposed which usually depend upon electromagnetic means for rendering the control circuit ineffective at the completion of a closing operation if the manual initiating switch remains closed. However, in most such arrangements, the closing operation could be initiated even though such electromagnetic means or antipumping means were defective and considerable damage to associated apparatus might result due to such defect, which permitted pumping of the device or the like. It would be desirable to provide an improved arrangement like the copending application referred to above in which no closing operation which might damage the actuating portions of the apparatus could occur if, for any reason, the electromagnetic means failed to respond when the manual switch to initiate the closing operation is actuated.

The previous arrangements often required complicated mechanisms in order to relate the mechanical motion of the main operating mechanism with the cutoff switch. It would be desirable to provide an arrangement in which a considerable simplification of the mechanism is possible.

Accordingly, it is an object of my invention to provide a new and improved control system for an electric circuit interrupter.

It is another object of my invention to provide an improved control system in which a considerable simplification of the mechanism may be obtained without any necessity for locating the cutoff switch in a manner convenient to the main operating mechanism so that the mechanical motion of the latter may be related to the cutoff switch.

It is a further object of my invention to provide an arrangement for preventing the repeated opening and closing of a circuit interrupter even though reversal of the circuit-breaker operating mechanism occurs at any time during the operating stroke.

Further objects and advantages of my invention will become apparent as the following description proceeds and the features of novelty which characterize my invention will be pointed out with particularity in the claims annexed to and forming a part of this specification.

For a better understanding of my invention, reference may be had to the accompanying drawing in which Fig. 1 is a partly diagrammatic layout of an electric control system and apparatus illustrating a specific embodiment of my invention, and Fig. 2 is a partly diagrammatic layout illustrating another modification of my invention.

As will be understood by those skilled in the art, any suitable motor means may be utilized for moving to a predetermined position, such as the closed position, the device to be operated, such as the circuit interrupter. Such motive means, as has been set forth in the copending application referred to above, may comprise motors of various sorts, such as fluid motors, pneumatic motors, dynamoelectric machines, solenoid motors, and the like, all of which may be controlled directly or indirectly by electric control means. In order to illustrate my invention, I have chosen in Fig. 1 to illustrate this motive means as comprising a fluid motor, generally indicated at 10, comprising a cylinder 11 and a piston 12 reciprocally mounted therein. Piston 12 is preferably connected to means to be actuated by longitudinally movable connecting rod 13. Preferably, connecting rod 13 is connected to an electric circuit breaker not shown, so that upward movement thereof causes closing of the circuit breaker.

Fluid motor 10 may be operated with any suitable fluid, such as air under pressure, for example, and, accordingly, the lower end of cylinder 11 is connected through conduit 14, valve 15 and conduit 16, only a portion of which is shown, to a source of fluid under pressure, not shown. When valve 15 is open to interconnect the source of fluid under pressure with the lower end of cylinder 11, upward movement of piston 12 and consequent closing of the circuit breaker results. For this reason, valve 15 will hereinafter be referred to as the circuit-breaker closing valve.

In order to open the circuit breaker, not shown, I provide means including conduit 17, circuit-breaker opening valve 18, and conduit 19, only a portion of which is shown, which is preferably connected to the same source of fluid under pressure as is conduit 16.

Circuit-breaker closing valve 18 may be operated in any suitable manner and is indicated as being provided with a solenoid 20 having a winding 21, which is energized to open valve 18 whenever opening of the circuit breaker not shown is desired. As will be understood by those skilled in the art, winding 21 is preferably automatically controlled in response to the conditions on the circuit controlled by the electric circuit breaker and, furthermore, should be manually controllable so that opening of the circuit breaker at the will of the operator may also be obtained. In order to maintain circuit-breaker opening valve in the closed position whenever the winding 21 of solenoid 20 is deenergized, I provide suitable means, such as spring 22, for biasing the valve member to the position indicated in Fig. 1.

The circuit-breaker closing valve 15 is also indicated as of the solenoid-controlled type including a solenoid 23 having a winding 23'. Valve 15 is normally biased to the closed position indicated in Fig. 1 by suitable spring means 24.

In order to control the closing operation of the circuit breaker, not shown, I provide an electrical control circuit including a suitable source of electrical energy, such as supply circuit 25. The energization of winding 23' of solenoid 23 from supply circuit 25 is controlled by electromagnetic means, generally indicated at 26. Electromagnetic means 26 includes a magnetic structure 27 having a single winding 28 thereon which controls two independent armatures 29 and 30, respectively, pivotally mounted about a common pin or pivot point 31. The inner armature 29 is light and constructed so as to be moved with a relatively small force acting thereon and is always maintained within the coercive zone of the electromagnet comprising magnetic structure 27 and winding 28 by means of a suitable stop 32 engaging an extension 33 of armature 29. Armature 29 is arranged to move so as to assume a vertical position against the pole piece of magnetic structure 27 upon energization of winding 28 so as to cause a switch 34 to bridge contacts 35 which are connected in series with the energization circuit of winding 23' of solenoid 23 so that, when armature 29 approaches its fully attracted position, winding 23' is energized to open circuit-breaker closing valve 15, thereby initiating the closing stroke of the circuit interrupter.

The second armature 30 is much heavier than the armature 29 and is normally held outside the coercive zone of the electromagnet comprising magnetic structure 27 and winding 28 by spring means 36 connected so as to cause armature 30 to pivot about pin 31 in a counterclockwise direction. Armature 30 is provided with an extension 37 connected to support a limit switch 38 which normally bridges contacts 39. When armature 30 is in the position indicated in Fig. 1, contacts 38 which are connected in the control circuit of winding 23' of solenoid 23 in series with the contacts 35 mentioned above, are closed.

The particular construction of armatures 29 and 30 is not important insofar as my invention is concerned and several different arrangements can be used. For example, armature 30 might be channel shaped so as to embrace armature 29 when both armatures are in the vertical position

or, as indicated in the drawing, armature 30 may be arranged in adjacent relationship to armature 29.

Although armature 30 in the unattracted position of Fig. 1 outside the coercive zone of electromagnetic means 26 cannot be pulled into the vertical or attracted position by energization of winding 28, nevertheless, if armature 30 were moved to such vertical position, the magnetic force of the electromagnet comprising magnetic structure 27 and winding 28 would be sufficient to hold armature 30 in the attracted or vertical position. In other words, armature 29 is constructed so as to be saturable, whereby there is an ample surplus of magnetic field available to hold armature 30 in the vertical or attracted position once it has been moved by an external force to this position.

Winding 28 of electromagnetic means 26 is preferably energized from supply circuit 25 through a push-button control or operator's switch 40 which may be manually closed by the operator to initiate the closing operation of the circuit breaker. This operation may also be automatically initiated by automatic reclosing switch 41 paralleling switch 40 which may be controlled in a manner well known to those skilled in the art. Seal-in contacts 42 controlled by switch member 43 are provided to parallel push button 40 to seal in the circuit of winding 28 of electromagnetic means 26 when the push button 40 is released.

The control circuit described thus far is disclosed and claimed in the copending application referred to above.

In order to deenergize the control circuit for the closing operation of motive means 10 in accordance with a predetermined operation thereof without requiring a predetermined relationship with respect to the position of armature 30 and connecting rod 13 as was required heretofore, I provide an auxiliary fluid motor, generally indicated at 44, including a cylinder 45 and a piston 46. Cylinder 45 is so positioned that, when piston 46 is moved to the right as viewed in Fig. 1, a longitudinally guided operating rod 47 connected to piston 46 moves armature 30 into the coercive zone of electromagnet 26 so that it may be held electrically in the vertical position until deenergization of winding 28 occurs. In order that this movement of armature 30 occurs when connecting rod 13 reaches a predetermined position during the closing stroke of the circuit interrupter, thereby moving member 47 against heavy armature 30 heretofore unresponsive in lying beyond the coercive zone of the electromagnet comprising magnetic structure 27 and winding 28, I connect the left-hand end of cylinder 45 of auxiliary fluid motor 44 through conduit 48 and conduit 48' to cylinder 49 at a point indicated at 49 intermediate the ends thereof. When piston 46 moves beyond the point 49 at which conduits 48 and 48' interconnects cylinders 45 and 49, fluid under pressure is permitted to enter the left-hand end of cylinder 45 and consequent movement of heavy armature 30 results. Just as heavy armature 30 is about to reach the vertical position against magnetic structure 27, limit switch 38 is moved away from contacts 39 to deenergize the control circuit of the motive means including fluid motor 44. As long as winding 28 remains energized, armatures 29 and 30 are held in the attracted positions against magnetic structure 27, thereby preventing pumping of the apparatus in the event that the circuit breaker is closed on an abnormal

condition on the system with which it is associated. The instant during the closing cycle of the circuit interrupter at which heavy armature 30 is moved is determined by the particular point 49 at which conduit 48' is connected to cylinder 11.

In order that the opening operation of the circuit breaker may be given preference over the closing operation, I interconnect the upper end of cylinder 11 with cylinder 45 through conduit 48'' and conduit 48 so that, whenever circuit-breaker opening valve 18 is opened, fluid under pressure is immediately admitted into cylinder 45 to move heavy armature 30 against magnetic structure 27 thereby opening limit switch 38 and, consequently, deenergizing the winding 23' of solenoid 23 controlling circuit-breaker closing valve 15.

In order to prevent fluid from flowing around the piston 12 in cylinder 11 when in the dotted position indicated in Fig. 1 through conduits 48' and 48'', I provide check valves 50 and 51, respectively, which permit fluid to flow only from cylinder 11 to cylinder 45.

It will be observed that, with the arrangement disclosed in Fig. 1, the motion of piston 12 may be reversed from the closing to the opening operation at any time during the operating stroke without danger of pumping since the moment opening valve 18 is opened, heavy armature 30 is moved so as to open cutoff switch 38 and it is not necessary to wait until a predetermined position of piston 12 has been obtained before this results as in the prior-art construction.

The operation of my invention will be well understood by those skilled in the art in view of the detailed description included above. A closing operation of the circuit breaker connected to rod 13 may be initiated by depressing push button 40 or by automatic closure of switch 41, 40 whereupon the winding 28 of electromagnetic means 26 is energized to attract armature 29 which is within the coercive zone thereof. Such operation of armature 29 causes switch 34 to bridge contacts 35, thereby energizing solenoid 23 to open circuit-breaker closing valve 15 and initiate the closing operation of fluid motor 10. When the circuit breaker controlled by the motive means comprising fluid motor 10 approaches its closed position, piston 12 has reached a position in cylinder 12 above point 49 so that fluid under pressure may enter conduit 48' and flow through check valve 50 and conduit 48 to cylinder 45, causing piston 46 to move member 47 so as to move heavy armature 30 against armature 29 which is in the attracted position with respect to magnetic structure 27, thereby opening limit switch 38 and deenergizing winding 23' of solenoid 23. As long as the operator's switch 49 or automatic reclosing switch 41 remains closed, winding 28 remains energized to hold heavy armature 30 in the attracted position so that only a single operation can occur and repeated closures or pumping of the circuit breaker will not result if the circuit breaker were closed on an abnormal current condition existing on the circuit which it controls. In the event that electromagnetic means should become defective, the circuit-breaker closing operation would not be initiated as in prior-art devices so that the danger of improper operation of the limit switch would not arise as was the case in such prior-art arrangements.

Where electromagnetic means 26 may be positioned close to the fluid motor 10 and connect-

ing rod 13, mechanical means, as illustrated in the copending application referred to above, may be utilized to operate heavy armature 30 directly in response to the position of connecting rod 13. 5 Accordingly, in Fig. 2, I have illustrated such an arrangement in which the corresponding parts of the apparatus and control system are designated by the same reference numerals as in Fig. 1. I have provided a cam 52 mounted on 10 longitudinally movable connecting rod 13 which engages with a horizontally movable member 53 whenever connecting rod 13 reaches a predetermined position so as to move heavy armature 30 in the same manner as was accomplished by member 47 in Fig. 1. In order to permit reversal of piston 12 at any time during the closing operation without pumping and also in order to give the opening operation of the circuit interrupter, not shown, preference over the closing operation, I again provide an auxiliary fluid motor, generally indicated at 54, comprising a cylinder 55 and a piston 56 operatively connected to a member 57 which engages an extension 58 on heavy armature 30. Cylinder 55 is connected by means 25 of conduit 59 to the upper end of cylinder 11 so that, whenever opening valve 18 is opened upon energization of winding 21 of solenoid 20, heavy armature 30 is immediately moved so as to open limit switch 38. It will be understood by those 30 skilled in the art that the arrangement disclosed by Fig. 2 operates similarly to that disclosed in Fig. 1 although the arrangement in Fig. 1 has the advantage in that the location of the cutoff switch and electromagnetic means 26 35 is not limited as in Fig. 2 where it is necessary to obtain mechanical motion directly from the main operating mechanism.

It should be understood that my invention is not limited to the specific details of construction herein illustrated and that changes and modifications may occur to one skilled in the art without departing from my invention. I, therefore, aim in the appended claims to cover all such changes and modifications as fall within the true spirit and scope of my invention.

What I claim as new and desire to secure by Letters Patent of the United States is:

1. In a circuit-interrupter controlling system comprising motive means for moving said circuit interrupter to the closed position, an electric control circuit for effecting the operation of said motive means, means including a first switch for rendering said electric control circuit effective to initiate operation of said motive means to move said circuit interrupter to the closed position, electromagnetic means having an armature for operating said first switch, means including an operator's switch for energizing said electromagnetic means to operate said first switch and initiate closing of said circuit interrupter, and fluid operated means responsive to a predetermined operation of said motive means for causing deenergization of said control circuit, said electromagnetic means being so constructed and arranged to maintain said control circuit in the deenergized condition as long as said operator's switch is closed regardless of the position of said circuit interrupter.

2. In a circuit-interrupter controlling system comprising motive means for moving said circuit interrupter to the closed position, an electric control circuit for effecting the operation of said motive means, electromagnetic operated means for causing energization and deenergization of said

control circuit to render said motive means effective and ineffective to close said circuit interrupter, means including an operator's switch for controlling the energization of said electromagnetic means to initiate the closing operation of said circuit interrupter, fluid operated means including a cylinder and a piston operative in response to a predetermined closing movement of said circuit interrupter for deenergizing said control circuit, and means responsive to the continued energization of said electromagnetic means for maintaining said control circuit in a deenergized condition as long as said operator's switch remains closed regardless of the position of said circuit interrupter.

3. In a circuit-interrupter controlling system comprising motive means for moving said circuit interrupter to the closed position, an electric control circuit for effecting the operation of said motive means, means including a first switch for rendering said electric control circuit effective to initiate operation of said motive means to move said circuit interrupter to the closed position, electromagnetic means including a plurality of armatures, one of which is arranged for operating said first switch, means including an operator's switch for energizing said electromagnetic means to operate said first switch and initiate closing of said circuit interrupter, and fluid-operated means responsive to a predetermined operation of said motive means for rendering said first switch ineffective to control the energization of said control circuit.

4. In a circuit-interrupter controlling system comprising a fluid motor including a cylinder and a piston for moving said circuit interrupter from one position to another, an electric control circuit for controlling the circuit-breaker closing operation of said fluid motor, electromagnetic operated means for causing energization of said control circuit to render said fluid motor effective and ineffective to close said circuit interrupter, means including an operator's switch for controlling the energization of said electromagnetic means to initiate the closing operation of said circuit interrupter, fluid-operated means responsive to a predetermined position of the piston of said fluid motor in said cylinder for de-energizing said control circuit, means for causing opening movement of said circuit interrupter, and means responsive to the operation of said last-mentioned means for rendering said control circuit ineffective to control said fluid motor so that opening of said circuit interrupter takes precedence over the closing operation thereof regardless of the position of said fluid motor.

5. In a circuit interrupter controlling system comprising a fluid motor including a cylinder and a piston for moving said circuit interrupter to the closed position, a first means for causing said piston to move in a direction to open said circuit breaker, a second means for causing said piston to move in a direction to close said circuit breaker, an electric control circuit for controlling the operation of said second means, fluid-operated means connected to a predetermined intermediate point on said cylinder for rendering said control circuit ineffective to cause further closing operation of said circuit breaker when said piston reaches said predetermined point in said cylinder during the closing operation, and

means for connecting said fluid-operated means to another point on said cylinder of said fluid motor to give said first means precedent over said second means.

6. In a circuit interrupter controlling system comprising a fluid motor including a cylinder and a piston for moving said circuit interrupter to the closed position, a first means for causing said piston to move in a direction to open said circuit breaker, a second means for causing said piston to move in a direction to close said circuit breaker, an electric control circuit for controlling the operation of said second means, fluid-operated means connected to a predetermined intermediate point on said cylinder for rendering said control circuit ineffective to cause further closing operation of said circuit breaker when said piston reaches said predetermined point in said cylinder during the closing operation, means for connecting said fluid-operated means to another point on said cylinder of said fluid motor to give said first means precedent over said second means, and a check valve interposed in the connections between said fluid-operated means and said cylinder to prevent interchange of fluid between said points on said cylinder.

7. In a circuit interrupter controlling system comprising a fluid motor including a cylinder and a piston for moving said circuit interrupter from one position to another, an electric control circuit for controlling the circuit breaker closing operation of said fluid motor, electromagnetic operated means for causing energization of said control circuit to render said fluid motor effective and ineffective to close said circuit interrupter, means including an operator's switch for controlling the energization of said electromagnetic means to initiate the closing operation of said circuit interrupter, means responsive to a predetermined position of the fluid motor for de-energizing said control circuit, means for causing opening movement of said circuit interrupter, and fluid-operated means responsive to the operation of said last-mentioned means for rendering said control circuit ineffective to control said fluid motor so that opening of said circuit interrupter takes precedence over the closing operation thereof regardless of the position of said fluid motor.

8. In a circuit interrupter controlling system comprising a fluid motor including a cylinder and a piston for moving said circuit interrupter from one position to another, an electric control circuit for controlling the circuit breaker closing operation of said fluid motor, electromagnetic operated means for causing energization of said control circuit to render said fluid motor effective and ineffective to close said circuit interrupter, means responsive to a predetermined position of the fluid motor for deenergizing said control circuit, means for causing opening movement of said circuit interrupter, and fluid-operated means responsive to the operation of said last-mentioned means for rendering said control circuit ineffective to control said fluid motor so that opening of said circuit interrupter takes precedence over the closing operation thereof.

ALEXANDER C. BOISSEAU.
